UNITED STATES PATENT OFFICE.

ALBERT E. WALDEN, OF BALTIMORE, MARYLAND.

OZONE-GENERATOR.

1,316,342.

Specification of Letters Patent. Patented Sept. 16, 1919.

Application filed January 29, 1916. Serial No. 75,000.

To all whom it may concern:

Be it known that I, ALBERT E. WALDEN, a citizen of the United States, residing at Baltimore, in the State of Maryland, have 5 invented certain new and useful Improvements in Ozone-Generators, of which the following is a specification.

This invention relates to improvements in ozone generators and the object of this invention is to provide in an ozone generator a construction that is simple and easily disassembled and repaired, and one that will allow cooling of both the inner and outer electrodes, or both inner and outer electrodes and dielectric, by means of water, air or other suitable fluid or liquid, or a combination of liquids, fluids and air. Further to so construct the said ozone generator that the parts can be readily removed, repaired 20 or replaced, and in which the operation can be noted and the size of the units reduced to such an extent that in case one fails to operate it will have no appreciable effect on the operation of the system as a whole.

25 The invention consists of the novel construction and arrangement of the parts and combination of parts hereinafter more fully set forth in the following specifications and pointed out in detail in the appended claims.

30 In the accompanying drawings,—

Figure 1 is a top plan view of my invention with the top removed.

Fig. 2 is a vertical longitudinal section of Fig. 1 with the top thereon.

35 Fig. 3 is a section of one of the outer electrodes composed of two sections held together by a snap ring.

Fig. 4 is a vertical section of Fig. 1 on the line X—X.

40 Fig. 5 is an enlarged detail perspective of one of the insulators.

Referring to the accompanying drawings forming part of this specification, and in which like letter references designate like parts throughout the several view thereof, I 45 designate an outer case which is made of cast iron or other suitable material, having a top D of suitable material, but preferably of glass or other transparent material, and

50 an inlet chamber M at one end, provided with the inlet pipe E, and an outlet chamber N at the opposite end (one or both ends of which are removable), provided with an inlet and outlet pipe H for the cooling medium. Between the chambers M and N is 55 an air chamber O formed by insulators C,

C, near each end thereof, which are provided with recesses X in the vertical center thereof, into which project the ends of the outer electrode B, which latter may be in one piece 60 or in sections held together by spring rings R, or other device. The openings P in the insulators, through which the inner dielectric and electrode pass, are slightly larger than the inner electrode and provide gas or 65 air passages that communicate with the spaces S and T, which latter are provided with inlet and outlet pipes J and K respectively for the inlet and outlet of the air to be ozonized. The dielectric A is made of 70 glass, quartz or other suitable material and may have a coating of metal on its inner surface if desired, in which event it would also act as both dielectric and electrode, and is placed within and projects through the 75 outer electrode B, leaving a space therebetween, this space being governed by the voltage and frequency employed, or a combination again of frequency and voltage, for the passage of the air or gas to be ozonized 80 or it may be said the plurality of tubes forming the electrodes and dielectrics are concentrically arranged. The water flowing through the dielectric A forms the inner electrode and forms the conductor from or 85 to the case I. The ends of the said dielectric A pass through the insulators C. C. the openings in which are larger than the dielectrics so as to allow air or gas to pass to chambers S and T, and through the inner 90 partition of and terminating in the chambers M and N. The said inner partitions of the chambers M and N are provided with brass stuffing boxes U having the nuts V threaded thereon and with suitable packing 95 W to form an air and water tight joint. The chamber O also has an inlet F and outlet G through which the air passes to cool the outer electrode B. The electric current is supplied through the wires L and L¹, the 100 latter being connected to the case I and grounded.

It should be noted here that this construction provides for cooling both the inner and outer electrode as well as a construction 105 that will permit of the removal of any sulfate that may be deposited on the electrodes.

While I have shown my invention designed to operate horizontally, it is obvious that the same may be used vertically with 110 slight changes in the construction thereof.

The operation of the device is as follows:

5 . The air or gas to be ozonized passes in through the pipe to the chamber S and then through the space between the inner electrode and the dielectric to the chamber T and out through the pipe K. The air for 10 cooling the outer electrode B passes into the chamber O through the inlet F and out through the outlet G. All or part of the air or gas to be ozonized may be passed into the chamber and used to cool the outer electrode B if desired.

15 The water, oil, gas or other fluid or liquid for cooling the inner dielectric A passes into the chamber M through the pipe E, then flows through the inner dielectric A to the chamber N and out through the pipe H, and acts as the inner electrode where water or a non-insulating liquid is employed for 20 cooling, but with oil or a similar liquid or gas the inner dielectric must be coated with metal or foil, or have an additional inner tube within the same which is connected to the case.

25 It is evident to those skilled in the art that alteration in the arrangement and construction of the parts, or combination of parts may be within the scope of the appended claims without departing from the spirit of my present invention.

30 Having thus described my invention, what I claim is:

1. An ozone generator comprising a casing with a plurality of compartments, two of which have removable ends, and three 35 of which are formed by the insulators and outer electrode; one or more outer electrodes mounted within said casing and having an inlet and outlet; and one or more dielectrics mounted within said outer electrodes and 40 having inlets and outlets and a space between said inner dielectric and electrode.

2. An ozone generator comprising a metal casing with a plurality of compartments having a removable top of transparent or 45 other suitable material, insulators secured in said casing, and one or more outer electrodes mounted within said casing and in the central compartment, having inlets and outlets, and an inner dielectric mounted concentrically within said outer electrode which latter is mounted in said insulators, having 50 a space between said outer electrodes and inner dielectric and having inlets and outlets.

3. An ozone generator comprising a casing 55 with a plurality of compartments, insulators secured within said casing forming additional compartments, the outer electrode or electrodes mounted in and having their ends secured within said insulators, and 60 having inlets and outlets, the inner dielectric or dielectrics projecting through said outer electrode or electrodes and mounted concentrically therein and leaving a space therebetween, the said dielectric having an inlet 65 and outlet, and also acting as the conductor to conduct the cooling element from one compartment to another.

4. An ozone generator comprising a casing 70 having a chamber at each end thereof, one of which has an inlet and the other an outlet; insulators within said casing and between said chambers forming additional chambers, an outer electrode having its ends mounted and secured within said insulators 75 to maintain the proper relation to the inner dielectrics, and having an inlet and an outlet, an inner dielectric or dielectrics extending through said outer electrode and insulators and maintained concentrically therein 80 and providing a space therebetween, and having their ends extending through stuffing boxes and terminating in the said chambers at each end of the casing.

5. An ozone generator comprising a casing 85 having a central chamber provided with an inlet and an outlet, and a small chamber at each end of said central chamber, one of which is provided with an inlet and the other with an outlet, an insulator secured 90 near each end of said central chamber forming a space between each insulator and the end chambers, one of which is provided with an inlet and the other with an outlet, an outer electrode having its ends projecting 95 into said insulators and communicating with the spaces between the insulators and the end chambers, and an inner dielectric extending through said outer electrode and insulators and having its ends terminating in 100 the said end chambers.

In testimony whereof I affix my signature in the presence of two witnesses.

ALBERT E. WALDEN:
